UNITED STATES PATENT OFFICE

JOHN MEEKER HIGH, JR., OF NEW YORK, N. Y., ASSIGNOR TO HOPKINS CORPORATION,
OF JERSEY CITY, NEW JERSEY, A CORPORATION OF DELAWARE

SOUND-PRODUCING DEVICE

Application filed September 3, 1925. Serial No. 54,204.

The general object of this invention relates to a sound reproducing device for use in connection with phonographs, loud speakers, radio receiving set, etc. and the principal 5 object is the production of a simple, efficient and economical unit for the production of sound waves from an electrical or other type of source.

A further object is to provide a unit of 10 this character which due to its simplicity of construction, affords an exceptionally advantageous commercial device for the uses to be set forth.

A very important object is to provide a 15 device of this character wherein reproduction of speech, music or other sounds, is secured with maximum volume and clarity and with minimum distortion.

Other objects will appear as the description 20 is developed hereinafter.

The invention consists substantially in the construction, combination, location and relative arrangement of parts, all as will be more fully hereinafter set forth, as shown 25 by the accompanying drawings and finally pointed out in the appended claims.

Referring to the drawings:

Figure 1 is a plan view of the back of my 30 device.

Figure 2 is a sectional view on the line 2—2 of Figure 1.

Figure 3 is an enlarged view taken on the line 3—3 of Figure 2.

Figure 4 is an enlarged view of the motor 35 and means for attaching it to the cone.

Figure 5 is a sectional view taken on line 5—5 of Figure 4.

Figure 6 is a sectional view of the cone 40 and motor taken on line 6—6 of Figure 1.

The same parts are designated by the same 45 reference numerals wherever they occur throughout the drawing.

An important feature of this invention is the combination of a cone and sounding 50 board of relatively large dimensions as the vibrating elements or diaphragm for the loud speaker. I am aware that flat diaphragms as well as cones have been used as the vibrating element, but it is my belief that the combination of the two is new with me.

I have found that by means of this combination a wonderful tone quality is produced. The relatively small cone reproduces the high notes while the sounding board reproduces the low notes. With this combination, it is possible to cover the whole range 55 of audible sounds without causing the production of extraneous and discordant sounds.

My device works best when the edges of the board are free to vibrate so that I propose 60 to mount the whole device on resilient supports such as cords, springs, rubber strips, or blocks, etc.

The whole unit may be mounted in a picture frame, the usual box, etc. 65

While I have shown a regular cone with a circular base and a rectangular sounding board, I do not desire to be limited to these particular physical configurations, as I realize 70 that a cone of any size and shape either regular or irregular and a board of any geometrical form either regular or irregular may be utilized with good effect. In making these elements, I also propose to make them of any desirable thickness which may be constant 75 or varied either regularly or irregularly. Also they may be ribbed or corrugated. The board may even be flexed into a curved form, such as a cylinder or half cylinder.

I also contemplate making the cone and 80 sounding board of any suitable material, such as cardboard, parchment, fiber board, wood, sheet metal, etc. In my preferred form, I make the cone of parchment and the sounding board of balsa wood. 85

It is also within the purview of my invention to place the cone at the center of the sounding board or at any other point. Also I may use one or more cones driven by the same motor or by individual motors. 90

Many other modifications and changes in details of construction, shape, size and material, as well as application of the invention will quickly suggest themselves to one skilled 95 in the art without departing from the spirit and scope of my invention, which I will define in my appended claims.

In the arrangement shown in the drawings, the rectangular frame 1, is composed of the side pieces, 2, 2, and the end pieces 3, 3 100

clamped together by the metal angle pieces 4, 4, 4, 4, and conventional wood screws. At each end of this frame is a rubber strip 5 attached at both ends to the side pieces, 2, 2.

5 The sounding board 6 is mounted in these strips as shown in Fig. 2 so that the vibrations of the board are absorbed before they reach the frame 1. In the center of the board 6, I have shown a circular opening 7 through 10 which the cone 8 extends. This cone has a flange 9, which is fastened to the board by glue, for example.

At the apex of the cone is a metal thimble 10, with a plurality of lugs 11, which may or 15 may not be glued to the cone as desired. On the inside of the cone at the apex is a small conical thimble 12 (Figure 6) for re-enforcing the cone.

At 13 I have shown by way of illustration 20 a motor of the balanced armature type for changing the electrical currents into mechanical movements as will be described. I intend, however, to use any suitable motor to operate this device.

25 The motor, (Figure 6) is composed of a cobalt steel permanent magnet 14 of the horseshoe type. Mounted between the poles 15, 15 of the magnet is a solenoid coil 16 with leads 17 attached to the binding posts 18.

30 Attached to the poles 15 are two laminated pole pieces 19 terminating on either side of the armature 20, which extends through the solenoid coil. A bracket 21 is rigidly fastened at 22 to the support 23 for the solenoid.

35 16. A rod 24 joins the free end of the bracket 21 and the armature 20, so that the armature vibrations may be transmitted to the bracket. A bolt 25 extends through the bracket 21, a rubber connection 26, thimble 10, cone 8 and thimble 12 and is secured therethrough by a nut 27, or a rubber connection only may be used if desired. Thus, the vibrations of the armature 20 are carried to the cone and thence to the board 6. Two pieces 40 of insulating material 28, 29 are clamped into the arms of the magnet 14 by a long bolt 30 and nut 31. The binding posts 18 are mounted on the piece 29. On the lower end of bolt 30 is an arm 32 held in position by two 45 jam nuts so that a rubber, felt, etc. ball 33 on the end of the arm may be made to press against the cone with any desired pressure and at any point. By means of this arm it is possible to dampen out any natural vibrations of the cone and thus prevent extraneous noises.

The motor 13 is mounted on a bracket 34 which is fastened to the side pieces 2, 2 of the frame in any suitable manner. If desirable, I can place rubber or felt cushions between the feet of the bracket 34 and the frame to keep out the vibrations of the motor.

When the voice currents are sent through the coil 16, the armature 20 will vibrate under 55 the influence of the electro-magnetic field set

up, and these vibrations will be transmitted to the cone and sounding board which will then be set in vibration causing sound waves of large amplitude.

What I seek to secure by United States Letters Patent, is as follows:—

1. In a sound reproducing device, the combination of a parchment cone and a flexibly suspended balsa wood sounding board rigidly connected to the periphery of the cone. 75

2. In a sound reproducing device, a frame, a cone and a sounding board mounted in said frame, said sounding board being carried by said cone, a vibratory motor for actuating said cone and a bracket carried by said frame 80 for supporting said motor.

3. In a sound reproducing device, the combination of a cone and a sounding board carried thereby, means for operating said cone and board and means for vibrating said cone and board and means to control the vibration of said cone. 85

4. In a sound reproducing device, a rigidly joined cone and sound board flexibly suspended from the cone, a motor, means for rigidly joining said cone and motor and resilient means for mounting said motor. 90

5. In a sound reproducing device, a frame, a cone, and sounding board unit, resilient connections between said frame and said unit 95 and means to vibrate said unit, said resilient mounting permitting the edges of the unit to vibrate freely.

6. In a sound reproducing device, a frame, a cone and sounding board freely and flexibly suspended therefrom to form a unit therewith, resilient connections between said frame and unit, an electrical vibratory means, means connecting said unit and said vibratory means and means for mounting said vibratory means on said frame. 100

7. The combination according to claim 6 characterized by the provision for damping out the natural vibrations of the cone. 105

8. In a sound reproducing device, the combination of a vibratory cone and a flexibly suspended balsa wood sounding board connected to the periphery of the cone. 110

9. A loud speaker comprising a cone, a plane vibratory unit freely and flexibly supported thereby, a motor, means for mounting said unit and said motor operatively together, and means for damping out the natural period of vibration of the cone. 115

In testimony whereof I have hereunto set 120 my hand on this first day of September, A. D. 1925.

JOHN MEEKER HIGH, JR.
